UNITED STATES PATENT OFFICE.

OSCAR W. MUELLER, OF CINCINNATI, OHIO, ASSIGNOR TO THE MUELLER MACHINE TOOL COMPANY, OF CINCINNATI, OHIO, A CORPORATION OF OHIO.

GROOVING ATTACHMENT FOR LATHES.

Application filed April 28, 1923. Serial No. 635,358.

To all whom it may concern:

Be it known that I, OSCAR W. MUELLER, a citizen of the United States, residing at Cincinnati, in the county of Hamilton and 5 State of Ohio, have invented certain new and useful Improvements in Grooving Attachments for Lathes, of which the following is a specification.

It is a practice to provide journals with 10 external grooves, and bearings with internal grooves, to form oil channels along which oil may flow in order to uniformly oil the journals and bearings throughout their 15 lengths. My invention is applicable for providing grooves employable for this purpose.

It is the object of my invention to provide a novel attachment for a metal turning lathe comprising means whereby reciprocations 20 lengthwise of the axis of the rotated work are imparted to a tool mounted on the cross-slide of the lathe, in order to provide the work with a groove extending about the axis of the work; further, to provide novel 25 means whereby such reciprocations may be parallel with the axis of the work or at an angle with relation to such axis; further, to provide supporting means for the tool and means for attaching the same to the 30 cross-slide of a lathe, and driving means for reciprocating the tool and means for attaching the same to the carriage of the lathe; further, to provide novel driving 35 means for said tool comprising a gear-housing on the rear of the carriage, and a shiftable driving connection between the gear-housing and a reciprocable tool-part; further, to provide such last-named shiftable driving connection with novel means 40 whereby the tool-part may be reciprocated at an angle to the axis of rotation of the work; further, to provide novel means whereby to mount the tool; further, to provide novel means whereby crossing grooves 45 may be cut into the work; and, further, to provide novel tool means whereby grooves may be cut into the outer periphery or the inner periphery of work.

The invention will be further readily understood from the following description and claims, and from the drawings, in which latter:

Fig. 1 is a front elevation of a lathe having my invention applied thereto, partly 55 broken away.

Fig. 2 is a plan view of a portion of the same, partly broken away, and with the cover of the gear-box removed for better illustration of the parts.

Fig. 3 is a vertical cross-section of the 60 same, taken on the line 3-3 of Fig. 2.

Fig. 4 is a vertical cross-section of the same, taken on the irregular line 4-4 of Fig. 2.

Fig. 5 is a cross-section of the same, taken 65 on the irregular line 5-5 of Fig. 2.

Fig. 6 is a longitudinal section of the same, taken on the irregular line 6-6 of Fig. 3.

Fig. 7 is a longitudinal section of the 70 same, taken in the plane of the line 7-7 of Fig. 4.

Fig. 8 is a longitudinal section of the same, taken on the irregular line 8-8 of Fig. 2, but showing a plurality of cutters 75 differently arranged.

Fig. 9 is a side elevation of the tool-rod, partly broken away and partly in axial section, showing the same arranged for receiving a tool at each end thereof, one of the 80 tools being applied directly to the tool-rod.

Fig. 10 is a detail taken in cross-section in the plane of the line 10-10 of Fig. 4.

Fig. 11 is a plan view of exemplifying 85 crossing grooves arranged to be cut upon the outer periphery of a shaft by means of my improved device, the same being laid out in plane, and one of the grooves shown in full lines and the other shown in dotted lines.

Fig. 12 is a plan view of my improved de- 90 vice, with lathe parts partly broken away, showing my improved device arranged for cutting a groove in the outer periphery of a piece of work held in the chuck of the lathe-head; and,

Fig. 13 is a similar view of the same, with the tool arranged for cutting an oil-groove in the tapered inner periphery of a piece of work.

The lathe to which my improved attach- 100 ment is applied may be any metal turning lathe of usual construction and comprise a usual bed 21 having ways 22, 23, thereon, on which a usual carriage 24 is arranged to be suitably fed lengthwise of the bed. A 105 usual cross-slide 25 is mounted on the carriage and is guided crosswise of the bed by a guide 26 on the carriage.

The work is received either between the head-center 31 and the tail-center 32, or is 110

suitably secured to the head-chuck 33 secured to the head-spindle. The head-spindle or quill is driven in usual manner, for instance, by means of pulleys 34.

5 The work is represented as a shaft 35 in Figs. 1, 2, 3 and 4, the outer peripheries of the journal portions 36, 37, of which are exemplified as having grooves cut therein; as a stud 38 in Fig. 12, the outer periphery 10 of which is receiving a groove; and as a taper-bearing 39 in Fig. 13, the inner periphery of which is receiving a groove.

Feed lengthwise of the bed is imparted to the carriage in usual manner in order to 15 position the carriage with the attachment mounted thereon in proper location for operating on the work. This lateral adjustment may be effected by the usual lead-screw 41, operated in usual manner, for 20 instance, by a system of gearing 42 and speed changing mechanism in a speed change box 43, the control handles of which are exemplified at 44, 45, for controlling the speeds of the lead-screw. The lateral 25 positioning of the carriage may also be accomplished by means of a usual rack 46 and a usual pinion 47 rotated by a suitable hand-wheel 48.

If the work is a shaft or other piece 30 located between the centers of the lathe, the same may be attached to the head-spindle by means of a usual lathe dog 51 in which one end of the shaft is clamped by a set-bolt 52, the dog having an arm 53 received 35 in one of the slots 54 of the head-plate 55.

If the work is a stud, bearing or other 40 short piece, the same may be clamped to the head-spindle by means of the usual clamping jaws 58 of the usual head-chuck 33, for clamping and centering the piece of work so that its axis is coincident with the axis of rotation of the rotated spindle.

I have exemplified the cutting tool and 45 its mounting on the cross-slide, and the housing which supports the reciprocating means for the cutting tool as mounted on the rear of the carriage.

The cutter mounting is suitably supported 50 on the cross-slide and is arranged to have cross-feeding movements imparted thereto, and is preferably also arranged for being set at various angles with relation to the axis of the work so as to operate upon tapered peripheries as well as peripheries 55 which are parallel with the axis of the work.

I have exemplified the mounting for the cutting tool as comprising a saddle 61, secured to the tool-slide 62 of the lathe, which serves as a cross-slide, shown adjustable by 60 means of a feed-screw 64 operating in a nut 65 secured to the swivel-block 66 of the lathe. There is a guide 63 between the tool-slide and the swivel-block. The swivel-block is rotatable on a vertical axis about 65 a stud 67, a usual index 68 indicating the

degree of angular adjustment of the swivel-block, the swivel-block being clamped to the cross-slide 25 after adjustment by means of usual T-bolts 69, the heads of which are received in T-slots 70, nuts 71 clamping 70 the parts together.

The saddle is exemplified as clamped to the tool-slide, which for the purposes of my invention is a cross-slide. The clamping is effected by means of the usual tool-post 75, the head 76 of the tool-post being received in a T-slot 77 extending crosswise of the tool-slide and being provided with a slot 78 and a clamping bolt 79. The saddle is provided with a tongue 81 extending 80 crosswise of the saddle and received in the upper portion of a T-slot 77 for normally positioning the saddle at right angles to the tool-slide. The saddle is provided with a hole 82 through which the tool-post 85 protrudes. A clamp-bar 83 is received through the slot 78, the ends of the bar impinging the wall of the hole 82 at the respective sides of the tool-post, the clamp-bolt 79 exerting 90 clamping force upon the bar to rigidly fix the saddle to the cross-slide.

A reciprocating tool-support 85 is supported on the saddle. Bars 86, 87, are respectively supported in bearings 88, 89, of the saddle. These bearings are shown located in bearing-blocks 90, 91. The bearing-blocks are adjustable up and down on the saddle on guide-faces 92, 93, and are clamped in adjusted positions by means of clamp-bolts 94, 95, received through slots 96 in the respective ends of the saddle, the bolts being threaded into the bearing-blocks for clamping the bearing-blocks in adjusted positions to the saddle. The bearings 89 are exemplified as clamp-bearings for 100 clamping the bar 87 to the saddle by means of clamp-bolts 97.

A cross-head 101 has bearings 102, 103, therein, received about the respective bars 86, 87, the bearing 102 being shown as a 110 clamp-bearing for clamping the bar 86 therein by means of a clamp-bolt 104. In this form the cross-head and the bar 86 form the tool-support. The bar 86 is arranged to reciprocate in the bearings 88, 115 and the bearing 103 in the cross-head is arranged to reciprocate on the bar 87 fixed in the bearings 89. The arrangement provides guided movement in widely spaced bearings 120 for the bar 86, which is exemplified as the tool-bar, for providing a firm support for the tool and preventing chattering in the cutting operation and insuring a smoothly cut groove.

The tools may be variously supported. 125 Thus I have in Figs. 1, 2, 6 and 8, exemplified a tool 111 secured in a nose 112 of a tool-block 113 by means of a set-bolt 114. The tool-block is provided with bearings 115, 116, about the bars 86, 87, the bearing 130

115 being shown as a clamp-bearing about the tool-bar 86, clamped to said bar by a clamp-bolt 117. The bearing 116 has guided movement on the bar 87. I have found such 5 mounting of the tool desirable when operating upon a piece of work located between the centers of the lathe, in order that the piece of work may be readily reached by the tool, while clearance space between the 10 piece of work and the tool-bar is provided for the crank mechanism for reciprocating the tool, as hereinafter described.

I have further exemplified the bar 86 as provided with a socket 119, in which a tool 120 is arranged to be received, this tool being exemplified as a double edged tool, having a cutting edge at each end thereof. The tool is clamped in the socket by means of a set-screw 121, threaded into the outer end 20 of the bar.

The bar 86 is at its other end provided with a taper socket 125, in which the taper shank 126 of a supplemental tool-bar 127 is arranged to be received and secured. The 25 supplemental tool-bar is provided with a tool-socket 128, a set-screw 129 securing the tool 130 in its socket. The supplemental tool-bars are especially useful for operating upon the inner peripheries of bearings, 30 either straight or tapered, and supplemental tool-bars of various diameters and tools 130 of various lengths are provided, for being readily received into bores of different diameters, one of which is shown at 131 in the bearing 39. The smaller the bore the 35 less will be the diameter of the supplemental tool-bar and the length of the tool, the taper shanks thereof, however, being the same for being interchangeably received in the taper socket 125. The tool-bar may be provided 40 with a suitable drift slot 133 for ejecting the supplemental tool-bar by means of a suitable wedge.

The tool-bar may be placed in its bearing 45 with either end thereof extending toward the head-stock of the lathe, and the tool-block 113 may be secured at any point in the length of said tool-bar, depending on the location at which the grooves are to be cut. 50 The cross-head is provided with a guideway 137 in which a crank-block 138 reciprocates. A crank-pin 139 is received in the crank-block and in a crank-arm 140 on a crank-shaft 141. The connection between 55 the crank-pin and the crank-block is preferably a universal connection, comprising a ball 142 fixed to the crank-pin and located in a socket 143, the wall of which partially surrounds the ball so as to maintain the ball 60 in the socket during axial strains on the crank-pin. The crank-block has tongues 144 at its side edges, received in undercut grooves 145 in the guideway of the cross-head, for maintaining the block in the 65 groove during axial strains on the crank-

pin which is fixed in the crank-arm. The crank-block is made of two parts, in each of which part of the socket 143 is located, the parts being connected by screws 146 to inclose the ball, which has universal movement therein. 70

The crank-arm is adjustable in its shaft so as to adjust the distance between the axis of the shaft and the axis of the crank-pin, thereby adjusting the lengths of reciprocation imparted to the tool. The crank-arm is movable endwise in a hole 151 in its shaft, the position of the crank-arm being indicated by the marks of an index 152 thereon. An annular flange 153 on the crank-pin 80 which aids in locating the crank-pin by being received against a flattened portion 154 of the crank-arm, is arranged to be received in a recess 155 in the outer wall of the hole 151 in the shaft 141, for adjusting the 85 crank-pin proximate to the axis of the rotation of the shaft, and thereby increasing the range of adjustment of the crank-arm, by providing for especially short lengths of reciprocations. 90

The crank-arm is rigidly secured to its shaft by means of a stem 156, the inner end of which has a tongue 157 received in a groove 158 in the crank-arm in order to prevent turning of the crank-arm. A set-bolt 95 159 is threaded in the outer end of the wall of the bore 160 in the shaft 141, and acts upon the stem in said bore to clamp said stem against the crank-arm and thereby fix the latter in its hole. 100

The shaft 141 has rotation and axial movements in bearings 161, 162, of a gear-housing 163. A worm-gear 164 rotates said shaft. Said shaft is provided with a spline 165, a key 166 in said worm-gear projecting 105 into the spline and maintaining rotative relation between the gear and said shaft while permitting endwise movements of said shaft in said gear during its rotation.

A worm 167 meshes with the worm-gear 110 and has a pinion 168 thereon. Said worm and said pinion rotate together, and are fixed to a shaft 169, as by means of a set-screw 170. The shaft 169 is rotatable in bearings 171, 172, in said housing. A gear 115 173 meshes with said pinion and is provided with a hub 174, rotatable in a bearing 175 in said housing. A shaft 178 is journaled in a bearing 179 in said housing and extends through said gear and hub. This shaft has 120 a spline 180 therein, into which a key 181 in the gear 173 projects, for causing combined rotation of said gear and said shaft throughout the positions of lateral adjustments of the carriage. 125

The gear-housing may form a lubricating chamber for the gears therein and be provided with a cover 182.

Means are provided for fixing the gear-housing to the carriage, preferably provid- 130

ing said gear-housing with one wall 185 of a guideway 186, the other wall of which is formed by a block 187 adjustable laterally in a guideway 188 in the gear-housing, the latter guideway and block being formed with a tongue and groove joint 189 for holding the gear-housing in place by means of clamping action of the block. The first-named wall of the guideway and the block 10 are formed with jaws received under the laterally extending overhanging walls of the usual guide 26 on the carriage of the lathe. A bolt 190 is journaled in the gear-housing and threaded into said guide-block for drawing the two walls of the guideway 186 toward each other and thereby clamping said gear-housing to the guide 26.

The gear-housing may be placed in adjusted positions on said guide to properly 20 locate the same with relation to the axial line of the work, and the adjustable clamp-block permits the gear-housing to be clamped to guides of different widths, to accommodate my improved attachments to 25 lathes of different sizes and makes.

The shaft 178 is further journaled in a bearing 191 of an arm 192 arranged to be secured to the bed of the lathe. This arm is arranged to be placed in adjusted positions, 30 dependent on the position of the gear-housing and the driving connection with the driving mechanism of the lathe.

This driving connection is shown as a sprocket-chain 193, received about a 35 sprocket-wheel 194 fixed to the quill of the lathe by being clamped between a usual shoulder 195 of said quill and the usual head-plate 55 or head-chuck 33, screwed over the threaded end 196 of the quill. A pin 197 40 may additionally connect the sprocket-wheel and the part thus screwed on the quill. The sprocket-chain is also received about a sprocket-pinion 198, fixed to the shaft 178 by means of a set-bolt 199.

In locating the parts, the gear-housing is placed in approximate position on the carriage, and a chain of suitable length selected to drive the sprocket-pinion from the sprocket-wheel, whereupon the gear-housing 50 is shifted forwardly or rearwardly to place proper tension upon the sprocket-chain while the shaft 178 is parallel with the axis of rotation of the head-spindle, whereupon the bearing-arm 192 is positioned in its proper relation to obtain the results mentioned. The bearing-arm is then clamped in place, as by means of a clamp-bolt 201 received through a slot 202 in said arm and received in a threaded hole in a lug 203 of a saddle 60 204 fixed to the lathe-bed by means of a bolt 205 received through a cross-piece 206 and a hole in said saddle, the ends of said cross-piece and saddle contacting opposite sides of the walls of said lathe-bed, a nut 208 65 clamping said parts in place.

If it is desired to apply my improved attachment to a lathe, the tool-saddle is secured to the cross-slide of the carriage. The tool-saddle is instanced as imposed upon the tool-slide, which serves as a cross-slide, with the indicator on the swivel-block registering zero, to show that the guideway of the tool-slide is perpendicular to the axis of rotation of the work. The gear-housing is mounted upon the rear end of the carriage, 70 being secured to the cross-slide guide, and the crank of the driving means is connected with the reciprocating cross-head. The sprocket-wheel 194 is clamped in place, the sprocket-chain being also connected, and the bearing-arm for the sprocket-end of the gear-shaft adjusted and clamped in position.

If the journal portions of a shaft are to be grooved, the shaft is inserted between the 85 centers of the lathe. A tool-block is mounted on the bars of the tool-saddle and a suitable tool fixed therein. The tool-block is located at that portion of the bars corresponding with the portion of the shaft which is to receive the oil-grooves. The left-hand end of the shaft in Figs. 1 and 2 is instanced as grooved, by crossing grooves 211, 212, while a single groove 212 in the right-hand end is being formed.

The carriage is adjusted laterally on the bed by means of the rack and pinion or the lead-screw, so as to position the tool in proper relation to the shaft to be grooved.

The cross-slide is thereupon moved toward the shaft by turning the handle 214, which is fast to the cross-feed screw 215, or such movement may be accomplished by power through the medium of the splined rod 216, suitably driven in usual manner, and connecting with the cross-feed screw 215 by means of a suitable train of gearing communicating motion to a pinion 217 rotatively secured to said cross-feed screw. The cross-feed screw in this instance has a nut 218 100 threaded thereto, which is fixed to the cross-slide by means of a clamp-bolt 219, which extends through a slot 220 in said cross-slide, for providing adjustment of position of the cross-slide with relation to the carriage and cross-feed screw crosswise of the bed.

A usual handle 225 controls the neutral position in said gearing or connects said gearing so as to rotate the cross-feed screw to the right or to the left for movement of the cross-slide toward the work or away from the work, with the tool either in front or in rear of the axis of the work. An arm 226 operates the usual half-nuts about the lead-screw for connecting or disconnecting the carriage with the lead-screw.

One of the forms of grooves cut by my improved attachment is exemplified in Fig. 11, in which a groove 211 is exemplified in full 130

lines and a crossing groove 212 is exemplified in dotted lines. These respective grooves on the inner periphery or outer periphery of an object represent substantially a figure 8. 5 The feeding of the cross-slide toward the work moves the tool into contact with the work, and such feeding, continuing after contact has been made while the work rotates, causes the tool to cut into the work to 10 form the groove.

In the exemplification shown there is one revolution of the work to each endwise movement of the tool, the configuration of a single continuous groove being imposed on 15 the work at each two revolutions of the work and reciprocation back and forth of the tool. The depth of the groove is determined by the adjustment of the cross-slide toward the work. The operation is rapid.

20 The portion of the shaft lengthwise of the shaft over which the groove extends is determined by the adjustment of the crank-arm. The closer the crank-pin is to the axis of rotation of the crank-shaft, the shorter 25 will be the length of work portion over which the groove extends, and the farther the crank-pin is away from the crank-shaft, the longer will be this portion.

20 Connection between the driving means for the crank-shaft and the tool is maintained during crosswise movements of the cross-slide by reason of the ball and socket connection between the crank-pin and crank-block and the tongue and groove connection 35 between the crank-block and the cross-head, with the result that during such movements the crank-shaft moves axially in the worm-gear. Assuming that a groove has been cut in a shaft, as exemplified at the right-hand 40 end of the shaft in Fig. 2, which groove laid out in plane is shown in full lines in Fig. 11, and assuming that it is desired to cut the same portion of the shaft with a crossing groove, the cross-slide is moved to move the 45 tool away from the shaft and the shaft turned 180 degrees, for instance, by locating its dog 51 in the opposite slot 54 of the head-block.

50 The tool is again moved toward the work, which it will contact at points opposite to the contacts thereof for making the first groove. The grooves formed have their corresponding portions at opposite sides of the work, for forming a double crossing figure 55 8, which, laid out in plane, is shown by the full lines and dotted lines of Fig. 11. Such crossing grooves are shown at the left-hand end of the shaft in Fig. 2.

60 When forming a groove in a short piece of work, exemplified by the stud 38 in Fig. 12, the tool-bar is so placed that a tool in its overhanging end will contact said stud and cut said groove, the adjustment of the carriage and cross-slide of the lathe being 65 made to effect such cutting. In this arrange-

ment the crank-arm may be moved close to or past the axis of the work. A single setting of the stud will enable a single continuous groove 227 to be cut. The stud is arranged for having a crossing groove cut 70 thereon by turning the same 180 degrees in its chuck, or by presenting the opposite cutting end of the tool against the rear of the work.

If it is desired to cut a tapering face, the 75 tool mounting is placed at an angle with relation to the axis of rotation of the work, as indicated in Fig. 13, in which the attachment is exemplified as cutting a groove 228 in a tapered bore. If the tapered bore is of 80 too small a diameter to receive the tool-bar and its tool, a reduced supplemental tool-bar 127 is employed having a tool of shorter length, and one of the grooves is cut into the inner periphery of the work. When the cutting of the groove is completed and it is desired to cut a crossing groove, the cross-slide is moved rearwardly by rotation of the cross-feed screw and the tool mounting 85 swung on its swivel mounting, so that the 90 tool-bar will extend at a corresponding angle at the other side of the axis of the work.

The cross-slide is then fed for the other end of the tool to contact the other side of the inner periphery. The feeding of the tool 95 for causing the tool to enter the work and the operation for causing reciprocations of the tool and rotations of the work result in a crossing groove being formed in the tapered inner periphery of the work. It 100 will be understood that the cutting edges at the opposite ends of the tools are oppositely presented to the work, one of them cutting when contacting an ascending face and the other cutting when contacting a descending 105 face. The feeding of the tool may be accomplished in the present instance by feeding the tool-slide, which is part of the cross-slide and serves the part of a cross-slide.

During such reciprocations of the tool 110 when placed at an angle with relation to the axis of the work, endwise movements are imparted to the crank-shaft by the ball and socket joint and tongue and groove slide connection between the crank-arm and the 115 cross-head, which maintain the driving connection between the crank-shaft and the tool throughout the different positions and adjustments of the tool.

Having thus fully described my invention, 120 what I claim as new, and desire to secure by Letters Patent, is:

1. In a grooving attachment for a metal turning lathe, the combination with the carriage, the cross-slide and work-turning 125 means of the lathe, of a tool-saddle on the cross-slide, a reciprocating tool-support thereon reciprocating lengthwise of the axis of said work-turning means, a housing at the rear of the carriage, driving means 130

thereon, connecting means between said driving means and said tool-support to reciprocate the latter, and cross-feeding means for said tool-support.

5 2. In a grooving attachment for a metal turning lathe, the combination with the carriage, the cross-slide, the head-stock and the live spindle of the lathe, of a tool-saddle on the cross-slide, a reciprocating tool-support thereon, a housing, means for releasably securing said housing to the rear of the carriage, driving means on said housing, connecting means between said driving means and said tool-support to reciprocate said 10 tool-support lengthwise of the axis of said live spindle, and cross-feeding means for said tool-support.

20 3. In a grooving attachment for a metal turning lathe, the combination with the bed, the carriage, the cross-slide and the head-stock of the lathe, of a tool-saddle, means for releasably mounting said tool-saddle on said cross-slide, a reciprocating tool-support on said tool-saddle, a housing, means for releasably securing said housing to the rear 25 of the carriage, driving means on said housing, connecting means between said driving means and said tool-support to reciprocate said tool-support lengthwise of said bed, and cross-feeding means for said tool-support.

30 4. In a grooving attachment for a metal turning lathe, the combination with the carriage, the cross-slide and the head-stock of the lathe, said carriage provided with a 35 cross-guide for said cross-slide, of a tool-saddle, means for releasably securing said tool-saddle on said cross-slide, a reciprocating tool-support on said tool-saddle, a housing, means for releasably clamping 40 said housing to the rear portion of said cross-guide, driving means on said housing, connecting driving means above said cross-guide between said driving means and said reciprocating tool-support to reciprocate the 45 latter, and cross-feeding means for said tool-support.

50 5. In a grooving attachment for a metal turning lathe, the combination with the carriage, the cross-slide and the head-stock of the lathe, said carriage provided with a cross-guide for said cross-slide, of a tool-saddle, means for releasably securing said tool-saddle on said cross-slide, including 55 means for swiveling said saddle with relation to the axis of said head-stock, a reciprocating tool-support on said saddle, a housing, means for releasably clamping said housing to the rear portion of said cross-guide, driving means on said housing, connecting driving means above said cross-guide between said driving means and said reciprocating tool-support to reciprocate the latter, and cross-feeding means for said tool-support.

60 6. In a grooving attachment for a metal

turning lathe, the combination with the carriage, the cross-slide, the head-stock and the head spindle of the lathe, of a tool-saddle, means for releasably securing said tool-saddle on said cross-slide, a reciprocating tool-support on said saddle, a housing at the rear portion of said cross-slide, means for adjustably positioning said cross-slide and said housing crosswise of the lathe with relation to the axis of rotation of said head-spindle, driving means on said housing, and connecting driving means between the latter and said tool-support for reciprocating said tool-support lengthwise of said axis.

7. In a grooving attachment for a metal turning lathe, the combination with the bed, the carriage, the cross-slide, the head-stock and the head-spindle of the lathe, of a reciprocating tool-support on the carriage, a cross-head therefor, a housing at the rear portion of the carriage, a crank-shaft thereon, and crank driving means between said crank-shaft and said cross-head proximate to the axis of rotation extended of said head-spindle.

8. In a grooving attachment for a metal turning lathe, the combination with the bed, the carriage, the cross-slide, the head-stock and the head-spindle of the lathe, of a tool-saddle on the cross-slide, a reciprocating tool-support on the latter, a cross-head therefor, a housing at the rear portion of said carriage, a crank-shaft thereon, means for adjusting said tool-saddle for locating said tool-support at an angle to the axis of rotation of said head-spindle, and crank driving means between said crank-shaft and said cross-head proximate to the axis of rotation extended of said head-spindle arranged to maintain driving relation with said cross-head during movements of said cross-head toward and from said axis.

9. In a grooving attachment for a metal turning lathe, the combination with the bed, the carriage, the cross-slide, the head-stock and the head-spindle of the lathe, of a tool-saddle on the cross-slide, a reciprocating tool-support on the latter arranged to reciprocate lengthwise of the axis of rotation of the head-spindle, a cross-head therefor, a housing, means for releasably securing said housing to the rear portion of the carriage, an axially slidable crank-shaft thereon, a crank on said crank-shaft, and operative connecting means between said crank and said cross-head resisting separation in axial directions.

10. In a grooving attachment for a metal turning lathe, the combination with the bed, the carriage, the cross-slide, the head-stock and the head-spindle of the lathe, of a tool-saddle on the cross-slide, a reciprocating tool-support on the latter arranged to reciprocate lengthwise of the axis of rotation of the head-spindle, means for adjusting

the direction of said reciprocation, a cross-head for said tool-support, a housing, means for releasably securing said housing to the rear portion of the carriage, a gear thereon, 5 an axially movable crank shaft maintaining driven connection with said gear during its axial movements, a crank, means for adjustably positioning said crank on said crank-shaft, and operative connecting means 10 between said crank and said cross-head resisting separation in axial directions.

11. In a grooving attachment for a metal turning lathe, the combination with the bed, the laterally adjustable carriage, the cross-slide and the work-turning means of the lathe, of a tool-saddle on the cross-slide, a reciprocating tool-support thereon, a cross-head on the latter, a gear-housing, means for positioning said gear-housing on the rear portion of the carriage, gearing therein, a crank-shaft journaled in said housing driven thereby, crank means between the latter and said cross-head proximate to the axis of rotation extended of said work-turning 25 means, and a drive-shaft extending lengthwise of said bed, having rotative drive-connection with said gearing during lateral adjustments of said carriage.

12. In a grooving attachment for a metal turning lathe, the combination with the bed, the laterally adjustable carriage, the cross-slide and work-turning means of the lathe, of a tool-saddle on the cross-slide, a reciprocating tool-support thereon, a cross-head on the latter, a gear-housing, means for positioning said gear-housing on the rear portion of the carriage, gearing therein comprising gears at right angles to each other, a crank connected with said cross-head arranged for resisting separation in axial directions, a drive-shaft, a crank-shaft, and rotative drive connections between said respective shafts and said respective gears permitting axial movements during continuance 40 of drive relations between said respective shafts and gears.

13. In a grooving attachment for a metal turning lathe, the combination with the bed, the laterally adjustable carriage, the cross-slide, the head-stock and the head-spindle of the lathe, of a tool-saddle on the cross-slide, a tool-support thereon reciprocating lengthwise of the axis of said spindle, a

cross-head on said tool-support, a gear-housing, means for positioning said gear-housing on the rear portion of said carriage, a crank-shaft for said cross-head, gearing in said housing for driving said crank-shaft and comprising a driving gear, a drive-shaft extending lengthwise of said bed arranged to maintain driving relation with said driving gear during lateral adjustments of said carriage, drive connecting means between said head-spindle and said drive-shaft, and an adjustable bearing bracket at 65 said head-stock for said drive-shaft.

14. In a grooving attachment for a metal turning lathe, the combination with the bed, the carriage, the cross-slide and the work-turning means of the lathe, of a tool-saddle on the cross-slide, a gear-housing at the rear of the carriage, driving means between the gearing on said gear-housing and the tool-saddle for reciprocating said tool-saddle lengthwise of the bed, means for feeding said cross-slide toward and from the axis of rotation extended of said work-turning means, means maintaining the driving connections in said driving means during said feeding movements, means for feeding said carriage lengthwise of said bed, driving connections between said work-turning means and the gearing in said gear-housing, and means maintaining said driving connections during adjustments of said carriage.

15. In a grooving attachment for a metal turning lathe, the combination with the bed, the carriage, the cross-slide and the work-turning means of the lathe, of a tool-saddle on said cross-slide, a reciprocating tool-support thereon, a gear-housing supported on the rear portion of said carriage, driving means between the gearing on said housing and said tool-support for reciprocating said support lengthwise of said bed, and means connecting said work-turning means and said gearing in definite relations for cutting a continuous groove in the work lengthwise of and surrounding the axis of said work.

In testimony whereof, I have hereunto signed my name in the presence of two subscribing witnesses.

OSCAR W. MUELLER.
